UNITED STATES PATENT OFFICE

170,296

VISION TESTING DEVICE

John T. Armbruster, Niagara Falls, N. Y., assignor
 to American Optical Company, Southbridge,
 Mass., a voluntary association of Massachusetts

Application April 23, 1952, Serial No. 19,449

Term of patent 14 years

(Cl. D57—7)

To all whom it may concern:

Be it known that I, John T. Armbruster, citizen of the United States of America, residing at Niagara Falls, in the county of Niagara and State of New York, have invented a new, original, and ornamental Design for a Vision Testing Device, of which the following is a specification, reference being made to the accompanying drawings, forming a part thereof.

In the drawings:

Fig. 1 is a front perspective view of a vision testing device, showing my new design; and

Fig. 2 is a rear perspective view thereof.

The characteristic features of the new design reside in the portions shown in full lines in the drawings.

I claim:

The ornamental design for a vision testing device, substantially as shown and described.

JOHN T. ARMBRUSTER.
